UNITED STATES PATENT OFFICE.

CYRUS W. SALADEE AND WM. VEECH, OF NEWARK, OHIO.

IMPROVEMENT IN MECHANICAL MOVEMENTS.

Specification forming part of Letters Patent No. 58,304, dated September 25, 1866.

To all whom it may concern:

Be it known that we, CYRUS W. SALADEE and WILLIAM VEECH, of Newark, county of Licking, State of Ohio, have invented a new and Improved Mode of Constructing a Mechanical Movement; and we do hereby declare that the following is a full and exact description thereof, reference being had to the accompanying drawings, and to the letters of reference marked thereon.

The nature of our invention consists, first, in the peculiar arrangement, hereinafter shown and described, of supporting the pitman K across or upon a line with the center of the driving-wheel A; and, second, in that of the peculiar arrangement of the corrugated driving-wheel A, in combination with the pitman K, and friction-rollers B B', so that at one revolution of the shaft supporting the driving-wheel the number of the strokes of the pitman is increased to any requisite degree of speed.

In the drawings, Fig. 1 represents a side elevation of the parts employed, and Fig. 2 is a top view of the same.

We intend applying our invention to mowing-machines, to impart an increased motion to the cutter-blade; also, for driving up-and-down jig-saws. We can also, by the application of our improved motion, construct a most cheap and simply-constructed sewing-machine. In short, we intend using it wherever a rapidly-working pitman is desirable in machinery.

By the use of this motion we can construct a mowing-machine with just about one-half the usual number of working-parts employed.

By reference to Plate 2, it will be seen that only two cog-wheels are required to transmit a rapid motion to the cutter-blade. The driving-wheels S' of the mower (shown by the drawing on Plate 2) are cast without cogs, a single cog-wheel, A', being secured upon the axle B² of the machine of as large diameter as the case will admit of, and which is made to mesh into the small cog-wheel A² on the end of the driving-shaft E, when, at each revolution of the latter, the cutter-blade makes ten strokes, or even a greater number, if the number of corrugations on the driving-wheel are increased.

We construct our improved mechanical movement substantially as follows: We first

determine the length of stroke we wish to give the pitman K, which will indicate the diameter of driving-wheel A. For example, we will say the stroke of the pitman shall be three inches. To get this, we draw the diameter of the wheel A, as indicated by the circle red line S. We now space off this circle to the number of strokes we want the pitman to make to each revolution of the driving-wheel A. This done, we draw the lines across the center and intersecting with the space-marks upon the circle S, as indicated by the black dotted line F; then from the No. 2 to 1 on line F gives the depth of the corrugation, which is equal to the stroke of the pitman—three inches.

That part of the pitman passing across the center of the driving-wheel is a frame, C, made of cast-iron, (or wrought,) within which the driving-wheel A and friction-rollers B B' are made to work, substantially in the manner clearly shown in the drawings.

The frame C of the pitman K is made to slide upon the center shaft E of the driving-wheel A, by means of the oblong slot v, (see Fig. 1,) so that the stroke of the pitman shall be exactly the same at any point of connection at its outer end, whether working at an angle, as represented by Fig. 1, or on a line parallel with the base-line X, or perpendicular.

The friction-rollers B B' are secured within the frame of the pitman, in combination with the driving-wheel A, substantially as represented in the drawings, Figs. 1 and 2.

On the front end of the pitman-frame C is cast solid the bilge P, into which is screwed the round wrought-iron pitman-rod K, and secured in position by the set-screw N. There are a variety of ways in which this pitman may be held in a central position across the center of the driving-wheel A, but we now think that the manner here shown is best. We therefore wish it to be distinctly understood that we do not limit our claim to the precise manner here shown of maintaining the pitman K across the center of the driving-wheel A, and working in combination therewith, as any other device that will hold it on a line across the center of the driving-wheel will answer the same purpose and produce the same result.

We have, in some of our experiments, con-

neeted the pitman to the driving-wheel A, without the use of the cog-wheels B B', by letting the ends of the frame C of the pitman bear directly against the corrugated surface of the wheel A; but the friction thus created upon the wearing parts we think an objection to such arrangement.

We have also, in our experiments, combined a plain, straight pitman, extending from J to L, (see Fig. 1,) entirely on one side of the driving-wheel A, discarding the use of the frame C, shown in Fig. 2, Fig. 3 being a top view of the arrangement last named. E is the shaft of the driving-wheel, A the wheel, C and K the pitman. B B' are the shoulders, made solid to the pitman, and made to serve as a substitute for the rollers B B' in Figs. 1 and 2. E² is a thin washer slipped over the shaft E, and against which the nut or tap E³ is screwed to hold the whole in position.

Fig. 2, on Plate 2, illustrates another manner of connecting pitman K to the driving-wheel A. In this illustration we have a double pitman, K K, connected to the frame C, and supported in the bearings C² and C³. In place of the friction-rollers B B', as shown on Plate 1, we form the projections C' and C', in connection with the frame C, as shown in the drawings.

We will here remark that if noise and clatter attend the working parts of the friction-rollers B B', Figs. 1 and 2, Plate 1, and driving-wheel A, the rollers may be set in sliding boxes, and kept pressed tightly up against the driving-wheel by means of india-rubber or spiral springs interposed between the sliding boxes and the frame of the pitman.

Having thus fully described our invention, what we claim as new, and desire to secure by Letters Patent, is—

1. Broadly, supporting and operating the pitman C K, Figs. 1 and 2, Plate 2, across and upon a line with the center E of the corrugated driving-wheel A, substantially as and for the purpose set forth.

2. The arrangement of the corrugated wheel A, in combination with the pitman C K, and friction-rollers B B', or their equivalent, in the manner and for the purpose substantially as shown and described.

In testimony that we claim the above we hereunto subscribe our names.

CYRUS W. SALADEE.
WILLIAM VEACH.
